WEB WINDING APPARATUS

Frank Raymund Nicholson, Buffalo, N. Y., assignor to
E. I. du Pont de Nemours and Company, Wilmington,
Del., a corporation of Delaware

Application December 30, 1953, Serial No. 401,134

5 Claims. (Cl. 242—65)

This invention relates to an apparatus for continuously winding a multiplicity of narrow strips of thin web, e. g., film, paper or fabric, on individual cores, and, more particularly, to an arrangement in such apparatus whereby proper web control and winding tension may be maintained.

An object of the present invention is to provide an apparatus for winding a multiplicity of continuous strips slit from a continuous web onto a multiplicity of individual cores. A further object is to provide such an apparatus for winding narrow strips of a film, paper, etc., upon individual cores to form rolls having smooth edges. A still further object is to provide such a winding apparatus wherein proper web control and uniform winding tension is maintained at all times. Other objects will be apparent from the description of the invention that follows.

The above objects are accomplished in accordance with the present invention by providing an apparatus comprising a multiplicity of individual rotatable primary driving means mounted freely on a common drive shaft, spacing means secured to said shaft for driving and separating each of said driving means, a multiplicity of secondary driving means rotatably mounted on a stationary shaft positioned parallel to said driven shaft, each of said first driving means being connected to a corresponding secondary rotatable driving means through a power transmitting linkage, and a multiplicity of individual pivot arms mounted upon said stationary shaft, said pivot arms being rotatable independently of said secondary driving means, the free ends of each of said pivot arms being provided with a rotatable chuck assembly, each of said chuck assemblies being connected to a corresponding secondary driving means through a power transmitting linkage, each of said chuck assemblies providing for rigid mounting thereon of a core upon which a continuous strip of a web is wound, each of said cores being in rotating contact with a common film driving roll.

The present apparatus may be more clearly described with reference to the accompanying drawings wherein:

Figure 1 is a simplified schematic drawing of a slitting apparatus embodying apparatus of the present invention;

Figure 2 is a front elevation of Fig. 1 showing the multiple wind-up arrangement of the present invention and the relative positions of the driving means, e. g., pulleys, and spacer rings, on the driven shaft and the driven elements associated therewith;

Figure 3 is a modification of Fig. 1 showing a preferred embodiment of the first and secondary drive means; and

Figure 4 is a mechanical drawing illustrating an assembly sectional view on the line 4—4 of Figure 3.

Figure 1 illustrates the path of a continuous length of a thermoplastic film F as it is unwound from a supply roll A and is thereafter slit by knife K positioned between supporting rolls B and C and then over the surface of the main film driving roll M. From the film

2

driving roll M (the film at this stage being in the form of multiple narrow strips), one strip of the film is wound upon a cardboard core E mounted at the free end of the pivot arm P of the apparatus of the present invention.

- 5 The next adjacent strip of film is wound upon core E' mounted at the free end of pivot arm P' and so on, i. e., each strip of film is individually wound on a separate core disposed as hereinafter described. In the description of the apparatus of the present invention shown in Figure 1, it should be understood that the apparatus comprised of parts D, E, G, H, P, etc., is substantially identical to the apparatus comprised of parts D', E', G', H', P', etc., and that the parts are duplicated in accordance with the number of strips of film to be wound.
- 10 Figure 1 is meant to illustrate the general type of slitting apparatus wherein the apparatus of the present invention is highly useful. It should be understood, however, that the present apparatus may be employed in any type of slitting apparatus wherein the slit lengths of film are ultimately conducted onto a roll of the type illustrated in Figure 1 as film driving roll M. An embodiment of the apparatus of the present invention, as shown in Figure 1, comprises a primary driving means in the form of a pulley H mounted freely or loosely, that is, not attached, to a positively driven cylindrical drive shaft D. These pulleys, when a multiplicity thereof are employed, as shown in Figure 2, are spaced apart from each other by metal spacer rings S, S', etc., which are keyed to the mandrel or shaft, these spacer rings being free to move axially or longitudinally on the drive shaft. The assembly is held together in close contact by applying a lateral thrust upon the assembly, for example, by compression springs 13 and 14; and by this arrangement the keyed spacer rings frictionally drive the individual pulleys. To provide for slippage between the interfaces of the metal spacer rings and the pulleys, the contacting surface are machined smooth. The pulley H mounted on the drive shaft D is connected by means of a belt G to a freely rotating compound pulley N mounted on a stationary shaft T positioned parallel to the drive shaft D. Immediately adjacent to the pulley N is a pivot arm P mounted on stationary shaft T and free to rotate on shaft T independently of pulley N. The free end of the pivot arm is provided with a short shaft or mandrel upon which is mounted a rotatable chuck arrangement Y which provides for rigidly mounting thereon a core E. The core E which may be of cardboard, wood, metal, plastic, etc., is in rotating contact with the surface of the film driving roll M; and the core E is positively driven in a direction opposite thereto. Although drive shaft D is always driven at a greater rotational speed than the pulley H slippage between spacer ring S and pulley H is ever present; and this provides for positively driving core E at a surface speed equal to the surface speed of film driving roll M. The chuck assembly on which the core is mounted is driven by means of a belt J linking it with the freely rotating compound pulley N mounted on the stationary shaft T at the fixed end of the pivot arm P.
- 15 It should be emphasized that the cores are positively driven by the driven shaft and associated driven elements at a surface speed equal to the film driving roll M in order that sufficient tension is maintained upon the strips of film being wound. As the roll W of film builds up, the rate of rotation of the roll will be decreased uniformly, causing increased slippage between the smooth contacting surfaces of the pulleys H, H' and spacer rings S, S' on the driven shaft. This slippage between smooth metal surfaces provides for maintenance of the proper degree of winding tension upon the strips of film.
- 20 It should be further understood that the present web winding apparatus is not restricted with respect to the

number of individual drive shafts which may be employed with web driving roll, M, of Figure 1. For example, a third drive shaft with a corresponding stationary shaft and the desired number of individual driving means for individual pivot arms, may be mounted in proper space relation with web driving roll M. Such an arrangement is necessary for winding strips of film or fabric as narrow as $\frac{1}{4}$ " because the width of the pivot arm structure necessary for providing a rigid structure would not permit mounting adjacent cores close enough to wind strips as narrow as $\frac{1}{4}$ ", that is, when only two drive shafts are employed.

The power transmitting linkage between each of the individual rotatable driving means and each secondary driving means may be in the form of belts driven by pulleys, as shown in Figures 1 and 2; or they may be linked through other suitable means so long as provision is made to permit slippage between the interfacial surfaces of the keyed spacer rings and the rotatable driving means mounted freely upon the drive shaft. A preferred means is to transmit power from the drive shaft to the secondary driving means mounted on the stationary shaft by gears instead of by means of pulleys and belts. This is for the purpose of providing for easier assembly and for eliminating the possibility of slippage which may occur between belts and pulleys. Figures 3 and 4 are illustrative of an individual embodiment of the present apparatus wherein gears are used as the power-transmitting means between the drive shaft and the secondary driving means mounted on the stationary shaft. These views show a portion of a drive shaft 3 upon which are freely mounted circular gears 4. By the term "freely mounted" is meant that the gear, or in other cases, a pulley, is merely slipped onto a cylindrical shaft, that is, in much the same manner as a washer is slipped on a rod, the fit being relatively close, but there being no connection between the gear or pulley and the driven mandrel. In Figures 3 and 4, the teeth of gear 4, frictionally driven by keyed spacer rings 2, intermesh with the teeth of gear 5 rotatably mounted upon stationary shaft 6. Gear 5 is combined with sprocket 7 which is connected to the chuck assembly 8 by means of a toothed belt 9. The chuck assembly 8 is rotatably mounted at the free end of pivot arm 10. A core 11 is shown mounted upon chuck assembly 8. The fixed end of the pivot arm 10 is positioned or fixed onto the stationary shaft 6 by means of eccentric clamps 12.

The chuck assembly on which the cores are rigidly mounted may vary in general construction, but such an assembly comprises a chuck and a collet. The assembly may rotate on journal bearings or on ball bearings. In particular, the collet should provide for rigid mounting of the core, that is, the core will not wobble. Types of collets which provide for substantially rigid mounting include a rubber cylindrical collet having metal strips embedded in the outer circumferential surface, the metal strips being positioned parallel to the axis of the cylindrical collet. Another type of collet comprises a number of circular spring belts separated by wedge-shaped rings. A screw ring serves to hold the assembly together and by applying a lateral thrust by screwing the ring, the belts are expanded radially. The expanded belts apply a pressure on the internal peripheral surface of the core, and thereby support the core rigidly upon the chuck.

The present apparatus is highly advantageous and generally applicable for winding strips of any type of web, e. g., thermoplastic film, foil paper, fabric, etc., which requires, or will only tolerate, light or low winding tension. In many cases, the physical properties of the material being wound require that only light winding tension be used. For example, in the case of polyethylene terephthalate film, winding of those films which are less than 1 mil in thickness and are less than 1" in width requires light winding tension. For example, in-

sufficient tension usually causes film wrinkling and lateral wander, and excessive tension causes film breakage. With other thermoplastic films, for example, polyethylene, winding strips having thicknesses less than 3 to 5 mils normally requires light winding tension. The term "thermoplastic" employed herein applies to webs formed from films, filaments, etc., of polyamides, polyvinylidene chloride, polyvinyl chloride, cellulose acetate, regenerated cellulose, polyethylene, etc., and particularly to webs formed from polyethylene terephthalate film.

I claim:

1. Web winding apparatus comprising in combination a positively driven drive shaft, a multiplicity of individual primary driving means mounted on said drive shaft for free rotation thereon, spacing means secured on said drive shaft for rotation therewith and arranged to maintain adjacent primary driving means in spaced relationship, said spacing means being in frictional driving contact with said primary driving means, a stationary shaft spaced from and parallel to the drive shaft, a multiplicity of individual secondary driving means rotatably mounted on said stationary drive shaft, each of said secondary driving means being aligned with a primary driving means, a power transmitting linkage connecting each of said aligned primary and secondary driving means, a plurality of pivot arms rotatably mounted on said stationary shaft, each arm being disposed adjacent a secondary driving means, rotatable core-supporting means mounted on the free end of each of said arms, a power transmitting linkage connecting each secondary driving means and the core-supporting means on the arm adjacent thereto, a core upon which web is wound rigidly mounted on each of said core-supporting means, and a web driving roll in peripheral rotating contact with said cores and webs being wound thereon.
2. Web winding apparatus according to claim 1 wherein said spacing means comprises a plurality of flat rings secured to said drive shaft.
3. Web winding apparatus according to claim 1 wherein said primary driving means, said secondary driving means, and the power transmitting linkage therebetween is comprised of intermeshing gears.
4. Web winding apparatus according to claim 3 wherein said spacing means comprises a plurality of smooth-faced flat rings secured to said shaft, the flat faces of said rings being in frictional driving contact with the side faces of said primary driving gears.
5. In a web slitting machine comprising a web supply from which continuous web is fed, means for slitting the continuous web into a plurality of continuous strips, a positively driven web driving roll over which said strips pass, and cores in peripheral rotating contact with the web driving roll and upon which said strips are wound, the improvement which comprises in combination a positively driven drive shaft, a multiplicity of individual primary driving means mounted on said drive shaft for free rotation thereon, spacing means secured on said drive shaft for rotation therewith and arranged to maintain adjacent primary driving means in spaced relationship, said spacing means being in frictional driving contact with said primary driving means, a stationary shaft spaced from and parallel to the drive shaft, a multiplicity of individual secondary driving means rotatably mounted on said stationary drive shaft, each of said secondary driving means being aligned with a primary driving means, a power transmitting linkage connecting each of said aligned primary and secondary driving means, a plurality of pivot arms rotatably mounted on said stationary shaft, each arm being disposed adjacent a secondary driving means, rotatable core-supporting means mounted on the free end

of each of said arms, a power transmitting linkage connecting each secondary driving means and the core-supporting means on the arm adjacent thereto, and one of said cores rigidly mounted on each of said core-supporting means.
